UNITED STATES PATENT OFFICE

161,156

FRAME FOR A HANDBAG

Mitchel R. Bienen, New York, N. Y.

Application August 9, 1950, Serial No. 11,689

Term of patent 7 years

(Cl. D87—3)

To all whom it may concern:

Be it known that I, Mitchel R. Bienen, a citizen of the United States of America, residing in New York, county of New York, and State of New York, have invented a new, original, and ornamental Design for a Frame for a Handbag, of which the following is a specification, reference being had to the accompanying drawing, forming part thereof.

Fig. 1 is a perspective view of a frame for a handbag, showing my new design.

Fig. 2 is a fragmentary rear view illustrating the frame in open position.

I claim:

The ornamental design for a frame for a handbag, substantially as shown.

MITCHEL R. BIENEN.
